UNITED STATES PATENT OFFICE.

ALBERT GOTTSCHALK, OF NEW YORK, N. Y., ASSIGNOR TO NATIONAL PNEUMATIC COMPANY, OF NEW YORK, N. Y., A CORPORATION OF WEST VIRGINIA.

DOOR-CONTROL SYSTEM.

Application filed September 11, 1920. Serial No. 409,737.

To all whom it may concern:

Be it known that I, ALBERT GOTTSCHALK, a citizen of the United States, residing at New York, county of Bronx, State of New York, have made a certain new and useful Invention 5 in Door-Control Systems, of which the following is a specification.

This invention relates to door control systems such as are employed in the street, 10 way, or elevated railway systems.

The object of the invention is to provide a system wherein the control of the doors on the car or train of cars is dependent upon the position of the car or train of cars relative to the station or platform.

A further object of the invention is to provide means whereby with a single manipulation from a single control station, all of the doors of the car or train of cars will be 20 simultaneously opened or closed.

A further object of the invention is to provide means whereby upon the manipulation from a single station of the control mechanism only the doors of the car or train of cars which are opposite to the platform will be controlled thereby.

A further object of the invention is to provide a system of the character above set forth which is simple, efficient in operation 30 and economical of installation and maintenance and wherein safety for the passengers boarding or alighting from the car or train of cars is secured, and, further, wherein electrical means is employed for effecting the control of the doors of the car or train of cars in a safe manner without employing any exposed energized portions of the electrical system.

Further objects of the invention will appear more fully hereinafter.

The invention consists substantially in the construction, combination, location and relative arrangement of parts, all as will be more fully hereinafter set forth as shown in 45 the accompanying drawings and finally pointed out in the appended claims.

Referring to the drawings:

Fig. 1 is a diagrammatic view in plan showing the last two cars of a train of cars 50 at a station platform.

Fig. 2 is a similar view showing the front two cars of a train of cars at the front end of a station or platform.

Fig. 3 is a similar view of the front end

of a car or train of cars projecting beyond 55 the control mechanism of a station platform.

Fig. 4 is a sectional view showing the relation of a car relative to the station platform and the control means employed in relation 60 to my invention.

The same part is designated by the same reference characters wherever it occurs throughout the several views.

It is among the special purposes of my 65 present invention to provide a system of door control wherein a single operator on the train or on the station platform may effect the simultaneous control of all doors of the car or train of cars which are accessible 70 to the station platform and to effect this control, as one illustration of my invention, electrically, but without any permanently energized rails or current conductors on the station platform to form a source of danger 75 to the passengers on the platform through accidental coming in contact therewith.

Referring to the drawings, I have shown at 1 a station platform provided with a conducting rail 2 located preferably beneath the 80 platform 1 and under the projecting portion thereof to render the same inaccessible from the platform. This conductor rail is normally out of contact with any source of power and consequently forms no source of 85 danger to the passengers. In accordance with my invention I supply current from any suitable source, for example, from the control line or third rail supply, which is employed to propel the car or train of cars 90 and thence by the operator to the rail 2 which I will term the door control rail. I thereafter utilize current from the door control rail for controlling the doors of the 95 car or train of cars which are opposite to the door control rail. By this means it will be apparent that the only time at which the door control rail will be energized will be when the car or train of cars is opposite thereto.

It is the present practice in this art to effect the opening and closing movements of the doors to permit passengers to alight from or board the car by means of pneumatic motors, the fluid pressure supply to and the exhaust thereof from which are controlled by magnet valves which in turn are controlled by an electric current as will be 105

readily understood. It is also the present custom to provide a door motor for each door and at least one magnet valve for controlling each door motor. In the drawings 5 I have diagrammatically illustrated the door motor at 3 and the magnet valve for controlling the same at 4, the door motor controlling the opening and closing movements of the door 5. It will be understood, of course, that when the magnet 4 is energized, 10 the door motor 3 will cause the door 5 to open and, similarly, when the magnet 4 in this illustration is de-energized, the motor 3 will cause the door 5 to close. Each car is 15 equipped with what I will term door shoes 6 and energizing shoes 7, both of which are adapted to bear yieldingly against the door control rail 2 so that, when a car or train of cars pulls into the station, the doors opposite to the station will have their respective shoes 6 in contact with the door control rail 2 and at least one shoe 7 will be in contact with the rail 2. Now it will be apparent that if current is supplied from any 20 source through the shoe 7 to the door control rail 2 to thereby energize the rail 2, the respective shoes 6 will tap current from the rail 2 and supply the same through wire 8 to the magnet valve 4 and thence to ground and 25 thereby cause the actuation of the motor 3 to open the door 5. This, of course, will occur for every door of the car or train of cars which is opposite to the platform or, in other words, which has its individual door shoe in 30 contact with the door control rail. 35

It will be apparent from the foregoing that it is immaterial where the control is effected, that is, whether it be from the car or train of cars or from a point on the station. I have illustrated the principle of my invention, however, as applied to a control effected from the first car of the train of cars, which car I have numbered 9, and wherein current is supplied from the source to the 40 wire 10 which is controlled by a switch 11, which switch when closed transmits the current to wire 12, shoe 7, door control rail 2, and thence to each and every one of the door shoes 6 of the car or train of cars which is 45 in contact with the rail 2 and which obviously is dependent upon the number of doors or cars and the length of the rail 2.

While I have shown my invention as applied to cars having front and rear doors, I 50 wish it to be understood that this is merely illustrative and that cars having any desired number of doors are contemplated. Likewise, it will be apparent that by extending the door control rail 2 to any desired length, within the limits, of course, of the station platform, it is possible to effect a simultaneous operation of all of the doors of any desired number of cars with the safety feature that all doors not opposite the 55 platform will remain inoperative. Also, as

is illustrated, one or more control points will be provided throughout a train of cars, dependent upon where it is determined to be desired or most efficient to have the control of the doors effected. Also, as above 70 stated, inasmuch as it is the supply of current to the door control rail that effects the desired operation of the doors it will be apparent to those skilled in the art that this need not be secured from the train itself but may be effected from any desired or suitable location. 75

Many modifications and changes in details will readily occur to those skilled in the art and I desire, therefore, to have the foregoing description and the illustrations forming a part thereof regarded in the illustrative sense as illustrating the principles of my invention rather than in the limiting sense and having shown and described a system embodying the principles thereof, what I claim as new and useful and desire to secure by Letters Patent is:— 80

1. In a door control system, and in combination with a station platform and one or more cars having doors and electrically operated means for controlling the doors, of a current conductor extending substantially parallel to the platform, a contactor for each door carried by the car and adapted to contact with the conductor when opposite the platform, said contactor being in electrical connection with said door controlling means, and means for supplying current to said conductor. 95

2. The combination with a station platform and a normally deenergized conductor rail, of one or more cars having doors, and electrically operated means for controlling the movements of said doors, means for establishing electrical connection between said rail and each of said electrically operated means which controls a door opposite to said platform, and means controlled from the car for supplying current to said rail. 100

3. The combination with a station platform and a normally deenergized conductor rail, of one or more cars having doors, and electrically operated means for controlling the movements of said doors, means for automatically establishing electrical connection between said rail and each of said electrically operated means which controls a door opposite to said platform, and means controlled from the car for supplying current to said rail. 110

4. The combination with a station platform and a normally deenergized conductor rail extending the substantial length thereof, of one or more cars having doors and an electrically controlled device for controlling the movements of each door, each of said electrically controlled devices being in circuit with a contactor adapted to automatically contact with said rail when its 120 125 130

respective door is opposite said platform, and means for supplying current to said rail.

5. The combination with a station platform and a normally deenergized conductor rail extending the substantial length thereof, of one or more cars having doors and an electrically controlled device for controlling the movements of each door, each 10 of said electrically controlled devices being in circuit with a contactor adapted to automatically contact with said rail when its respective door is opposite said platform, and means controlled from the car for supplying current to said rail.

15. The combination with a station platform and a normally deenergized conductor rail extending the substantial length thereof, of one or more cars having doors and 20 an electrically controlled device for controlling the movements of each door, each of said electrically controlled devices being in circuit with a contactor adapted to auto-

matically contact with said rail when its respective door is opposite said platform, 25 said car also having a contactor in circuit with a source of current and adapted to automatically contact with said rail.

7. The combination with a station platform and a normally deenergized conductor rail extending the substantial length thereof, of one or more cars having doors and an electrically controlled device for controlling the movements of each door, each 30 of said electrically controlled devices being in circuit with a contactor adapted to automatically contact with said rail when its 35 respective door is opposite said platform, said car also having a contactor in circuit with a source of current and adapted to automatically contact with said rail, and means for controlling said last named circuit.

In testimony whereof I have hereunto set my hand on this 7th day of Sept., A. D., 1920.

ALBERT GOTTSCHALK.
